UNITED STATES PATENT OFFICE

2,112,692

CHANGEABLE EXHIBITOR

Charles M. Dennis, Otsego, Mich.

Application January 18, 1937, Serial No. 121,140

19 Claims. (Cl. 40—36)

The main objects of my invention are:

First, to provide a changeable exhibitor or display device for successively presenting cards of a stack of display cards or panels, which cards or panels are provided with advertising matter, pictures, news, or other matter to be exhibited or displayed.

Second, to provide a device of the type described which is efficient and unfailing in action.

Third, to provide a device of the type described which is exceedingly simple in its parts and economical of production.

Fourth, to provide a device of the type described which is adjustable in character and capable of accommodating display cards or panels, etc., of varying size and nature.

Fifth, to provide a device of the type described which is capable of presenting a card or panel of considerable area in comparison to or relative to the size of the device itself.

Further objects relating to details and economies of my invention will definitely appear from the description to follow. The invention is defined in the claims.

A preferred embodiment of my invention is illustrated in the accompanying drawing, wherein:

Fig. 1 is a view in perspective of a structure embodying my invention.

Fig. 2 is an enlarged view in section on a line corresponding to line 2—2 of Fig. 1 and generally illustrating the mechanism of my invention.

Fig. 3 is an enlarged fragmentary view illustrating details of the picker or pickup finger of my invention, the same being shown in position just prior to engagement with a card to elevate and advance the same to display position.

Fig. 4 is a fragmentary view in horizontal section on a line corresponding to line 4—4 of Fig. 5, further illustrating details of the picker of my invention.

Fig. 5 is an enlarged fragmentary view in section on a line corresponding to line 5—5 of Fig. 4, still further illustrating the details of the picker structure and showing the same in dotted lines in its position after the cards have been released.

Referring to the drawing, the reference numeral 1 in general indicates the casing or housing enclosing the operative structure of my invention and provided with a display opening 2 in the front wall thereof. The housing 1 may be formed of any suitable material; however, I preferably employ a sheet metal structure and cut the opening at the bottom thereof. It may be noted that due to the features of construction 55 to be hereinafter described opening 2 may be

made comparatively large to permit the exhibition of relatively large cards or display panels which are indicated by the reference numeral 3. I employ a stack made up of a plurality of these cards 3 which normally rest on an inclined seat 4 whereby the same are urged rearwardly, or whereby they tend to slide rearwardly.

The cards are supported at the rear of the stack by a pair of spaced inclined depending fingers 5 which are adjustable forwardly and rearwardly to accommodate more or fewer cards in a manner to be hereinafter described.

I provide a pair of depending blade springs 9 fastened at their upper ends 10 to the housing on either side of opening 2, these springs being comparatively weak and exerting a slight force on the front card 3 tending to urge the pack of cards rearwardly against rear support fingers 5. However, the strength of springs 9 is such that the cards may be readily withdrawn and likewise may be dropped at the front of the stack behind the springs by mechanism to be hereinafter described. Each of the cards is provided with a hole 11 adjacent the upper edge thereof for a purpose which will likewise be hereinafter brought out. The front side of the hole is covered by a suitable tab 111 adhesively secured to the card, or the hole may be covered by other means.

At a suitable point interiorly of housing 1, I provide a platform 12 having adjustably mounted thereon a support plate 121 which is slotted at 122 to receive bolts and nuts 123 whereby the plate may be adjusted forwardly or rearwardly on platform 12. A small motor 13 is mounted on plate 121 and has a shaft 14 which drives the shaft 15 of a pulley suitably journaled on plate 121 by reduction gearing consisting of a worm 16 on shaft 14 meshing with a worm wheel 17 on shaft 15. Motor 13 may be connected to a source of electric current in any suitable manner. The fingers 5 are integral at their upper ends with plate 121.

The pulley shaft 15 is suitably carried by a bracket 18 which is mounted on plate 121. The bracket extends upwardly from the plate and is pivotally and adjustably connected to the lower part 181 of an upwardly extending longitudinally adjustable pulley support by wing nut 182 on the pivot 183. The upper part 184 of the pulley support is slotted at 185 to receive screws 186 and wing nuts 187 whereby the length of the pulley support may be adjusted when the position of shaft 15 is changed. Support part 184 is provided at its upper end with a suitable spindle 19 whereon a second pulley is mounted. The pul-

leys carried on shaft 15 and spindle 19 are numbered respectively 20 and 21. The belt 22 is supported and driven by these pulleys. A belt of small section, so as not to impose a serious load 5 on motor 13, is preferable. I contemplate that a chain may also be employed in place of a belt transmission.

From the foregoing, it will appear that when it is desired to shift fingers 5 forwardly or rearwardly to accommodate more or fewer cards 3, the motor 13, belt 22 and parts associated therewith are simultaneously and similarly shifted without changing the operative relation of the parts in any way. This is accomplished by 15 simply loosening and shifting plate 121.

A release or trip 23, the function of which will be hereinafter more particularly pointed out, is secured to bracket 18 by one of the screws 186. The trip, in the embodiment illustrated, is formed 20 of wire and is provided with an eye 24 at the lower end thereof receiving the screw. The wing nut 187 may be tightened to secure the trip in adjusted position.

In Figs. 3, 4, and 5, I illustrate the details of 25 the picker or pickup finger which comprises an L-shaped bracket member 27 fixedly secured to belt 22 on the outer side or surface thereof by rivet 28. The bracket 27 forms a support for a tiltable finger 29, the finger being pivotally 30 mounted on the bracket by means of a pivot pin 30 extending through the finger and bracket. A spring 31 encircling the pin and bearing at its opposite ends against bracket 27 and finger 29, respectively, serves to maintain the same in operative position whereby the finger 29 will engage a hole 11 in the rearmost card of the stack when the finger is presented to the card by belt 22.

Spring 31 is a relatively weak one, its purpose 40 being merely to return the finger to operative or erected position, and it is sufficiently weak to be overcome by the weight of the card 3.

In order to hold finger 29 rigidly while the 45 same is lifting the rearmost card 3 and transporting the same forwardly and upwardly during the upward travel of finger 29, I provide a bolt or detent member 32 in the form of a forwardly curved tongue overhanging the inner end 33 of finger 29. The bolt member is pivotally 50 mounted in a pair of downturned wings or ears 34 integral with bracket 27 and has integral therewith a rearwardly extending arm 35 which engages the trip member 23 as the finger reaches the discharge position. Torsion spring 36 surrounds the pivot of bolt member 32, urging the 55 same to latching engagement with the inner end 33 of finger 29 by the engagement of the center portion 37 and ends 38 of the spring with the bolt member and wings 34, respectively.

From the preceding description, it will be seen 60 that when the finger travels downwardly and around the bottom of bottom pulley 20, it reaches the position illustrated in Fig. 3, with bolt member 32 locking finger 29 in erected position, the finger 29 passing upwardly against the rear of rearmost card 3. When it encounters opening 65 11 therein, the finger 29 operatively engages with the opening as illustrated in Fig. 5, lifting the rearmost card upwardly and transporting the same upwardly and forwardly in the manner shown in Fig. 2. Tabs 111 covering the holes 11 at the front thereof prevent the finger from lifting more than one card at a time.

When the card reaches its uppermost position, 70 or the position shown in Figs. 2 and 5, arm 35

engages a lug 39 offset from trip 23, with the result that arm 35 is rocked downwardly by the trip, as illustrated in dotted lines in Fig. 5. This releases the latching action of bolt member 32 and finger 29 is left unsupported except for spring 31, which was stated to be insufficient in strength to sustain a card 3. The finger is accordingly rocked downwardly, or in clockwise direction as viewed in Figs. 2, 3, 4, and 5, with the result that card 3 drops off the forward end of 10 the finger into position in front of the pack of cards 3 and past the blade spring retaining member 9.

In this manner, any number of cards may be 15 successively exhibited at opening 2, in a wide variety of shapes and sizes, the number of fingers 29 being as desired. It will, of course, be clear that adjustments for the position of fingers 5 with corresponding adjustments of the motor and belt and alteration of the position of 20 release trip 23 may be made as desired to accommodate varying numbers of cards.

For the purpose of illuminating cards which are displayed, I provide electric lamp 40 at a suitable point within the casing. Due to the action of the pickup finger in elevating, advancing, and dropping successive cards 3, it will be found that an unusual lighting effect characterizes the device of my invention. Fingers 29 may be so proportioned as to tilt the whole pack of 30 cards 3 forwardly during the time that the fingers are in engagement with the cards and while they are passing into opening 11. This will result in a sealing or partial sealing of the opening 2, cutting off light from the exposed face of the 35 front card. As soon as the rearmost card has been removed, however, and elevated, the pack of cards 3 falls backward against the rear supporting fingers 5, allowing the light from lamp 40 to illuminate the foremost of the cards for a 40 predetermined period before being again cut off in the manner described. This will produce a blinking or intermittent effect which is certain to attract attention to the display device and the cards exhibited thereby.

From the foregoing description, it will be apparent that I have provided a device which is simple in construction, efficient and unfailing in action, and which permits the exhibition of cards of relatively large dimensions due to the fact 50 that nothing other than the engagement of the pickup finger in hole 11 is employed for elevating and dropping the cards. My invention eliminates the need for picker frames and other cumbersome details characterizing devices which 55 are known in the art.

I have illustrated and described my improvements in an embodiment which I consider very practical. I have not attempted to illustrate or describe other embodiments or adaptations as 60 it is believed this disclosure will enable those skilled in the art to embody or adapt my improvements as may be desired.

Having thus described my invention, what I claim as new and desire to secure by Letters Patent is:

1. In a display device, a housing having a display opening in the face thereof, means for supporting a vertical stack of display cards in said housing behind said opening, each of said cards 70 being provided with a hole, means for removing cards successively from the rear of said stack and depositing the same at the front of the stack adjacent the opening, comprising flexible drive means, means including reduction gearing for 75

- finger in erected position, and means to release said card from said finger when the card has been elevated and advanced by the finger.
8. In a display device, a housing having a display opening in the face thereof, means for supporting a stack of display cards in said housing, means for removing cards successively from said stack and depositing the same next to the opening, comprising a conveyor, a pickup device on said conveyor adapted to engage said cards successively, said pickup device comprising a card engaging finger, a finger latching member, and means to release said latching member from said finger when the card has been elevated and advanced by the finger, comprising a release arm on the latching member and a trip in the path of movement of said arm and adapted to rock the arm in opposition to the spring urging the latching member and release the same, the weight of the card overcoming the force of the spring urging the finger whereby the finger rocks downwardly.
9. In a display device, an endless conveying means, means for driving the same, a rockable card engaging member carried by said conveying means, means carried by said conveying means and movable into engagement with the member for latching said member in operative card engaging position, means for urging said latching means to latching position, adjustable means for releasing said latching means to permit the discharge of a card by rocking of said member, and spring means for returning the member to operative position after it has been rocked to discharge the card.
10. In a display device, an endless conveying means, means for driving the same, a rockable card engaging member carried by said conveying means, means movable into engagement with the member for latching said member in operative card engaging position, means for urging said latching means to latching position, means for releasing said latching means to permit the discharge of a card by rocking of said member, and means for returning the member to operative position after it has been rocked to discharge the card.
11. In a display device, a housing, a stack of cards in display position in said housing, each of said cards having a hole therethrough and a tab covering the front side of the hole, an endless belt, means for driving the same, an engaging member adapted to engage said holes and pivotally mounted on said belt to project therefrom, means for latching said member in operative card engaging position, means for releasing said latching means to discharge a card, and spring means for returning the member to operative position after it has been rocked to discharge the card.
12. In a display device, a housing, a stack of cards in display position in said housing, each of said cards having a hole therethrough and a tab covering the front side of the hole, an endless belt, means for driving the same, an engaging member adapted to engage said holes and pivotally mounted on said belt to project therefrom,
- means for latching said member in operative card engaging position, means for releasing said latching means to discharge a card, and an adjustable support for said belt and releasing means.
13. In a display device, a housing, a stack of cards in display position in said housing, each of said cards having a hole therethrough and a tab covering the front side of the hole, an endless belt, means for driving the same, an engaging member adapted to engage said holes and pivotally mounted on said belt to project therefrom, means for releasing said card engaging member to discharge a card, and an adjustable support for said belt and releasing means.
14. In a display device, a housing having a display opening therein, a support for a stack of cards behind said opening, a conveyor having means for transposing a card from the back of said stack to the front thereof, means for driving said conveyor, and means for simultaneously and similarly adjusting said support, conveyor and drive means forwardly or backwardly to accommodate the size of said stack.
15. In a display device, a housing having a display opening therein, a support for a stack of cards adjacent said opening, a conveyor having means for moving a card to said opening, means for driving said conveyor, and means for simultaneously and similarly adjusting said support and conveyor.
16. In a display device, a rockable card engaging member and means carrying said member to position to engage and lift a display card, means to hold said member in card engaging and supporting position, and means operative at a predetermined time to release said holding means from said member whereby the weight of the card causes the member to rock and discharge the card.
17. In a display device, a card engaging finger, means for transporting said finger in an endless path to successively engage and lift a plurality of cards, said cards each having a finger receiving hole therein and a tab closing said hole at one side of the card whereby the extent to which the finger penetrates the card is limited, and means comprising a member carried by said transporting means for discharging the card from said finger.
18. In a display device, a card engaging finger, means for transporting said finger in an endless path to successively engage and lift a plurality of cards, said cards each having a finger receiving recess closed at one side of the card whereby the extent to which the finger penetrates the card is limited, and means comprising a member carried by said transporting means for discharging the card from said finger.
19. In a display device, a card engaging finger, and means for transporting said finger in an endless path to successively engage and lift a plurality of cards, said cards each having a finger receiving hole therein and a tab closing said hole at one side of the card whereby the extent to which the finger penetrates the card is limited.

CHARLES M. DENNIS.
